UNITED STATES PATENT OFFICE.

FREDERICK W. GEHRKE, OF WEST COLLINGSWOOD, NEW JERSEY, ASSIGNOR TO THE HORN AND BRANNEN MANUFACTURING COMPANY, OF PHILADELPHIA, PENNSYLVANIA, A CORPORATION OF PENNSYLVANIA.

DESIGN FOR AN ORNAMENTAL SHELL FOR GAS AND ELECTRIC LIGHT FIXTURES.

43,141.

Specification for Design.

Patented Oct. 15, 1912.

Application filed June 14, 1912. Serial No. 703,749. Term of patent 7 years.

To all whom it may concern:

Be it known that I, FREDERICK W. GEHRKE, a citizen of the United States, residing in West Collingswood, county of Camden, State of New Jersey, have invented a certain new, original, and ornamental Design for Ornamental Shells for Gas and Electric Light Fixtures, of which the following is a specification, reference being had to the accompanying drawing, forming part thereof.

Figure 1 is the plan view of the exterior surface of the shell, and Fig. 2 a side elevation thereof.

The shell and the design impressed thereon, are stamped up in sheet metal, and the exterior shape of the shell is necessarily such as to give depth to it, providing thereby a hollow interior, as indicated in Fig. 2. The central opening in the shell is surmounted

by an axially-disposed rim, from the base of which proceeds outwardly, six identical series of radially-disposed concave flutes, of unequal length in each series, and widening outwardly from the aforesaid radial center, and the outer edges of the flutes being curved to produce the appearance of a corrugated edge to the flutes in the several series, and the six series, so assembled, as shown in Fig. 1, producing the appearance somewhat of a six pointed star.

I claim:

The ornamental design for a shell for gas and electric light fixtures, as shown and described.

FREDERICK W. GEHRKE.

Witnesses:

A. M. BIDDLE,
R. A. DUNLAP.
